UNITED STATES PATENT OFFICE.

JESSE H. SROFE, OF KOKOMO, INDIANA.

DESIGN FOR A WIRE FENCE.

SPECIFICATION forming part of Design No. 30,421, dated March 28, 1899.

Application filed February 15, 1899. Serial No. 705,582. Term of patent 7 years.

To all whom it may concern:

Be it known that I, JESSE H. SROFE, a citizen of the United States, residing at Kokomo, in the county of Howard and State of Indiana, have invented and produced a new and useful Design for Wire Fences, of which the following is a specification.

In the drawing I have shown a side elevation of a wire fence, presenting my design. 10 As shown in the drawing, the leading or important features of my design consist in the fence having the horizontal or strand wires A, B, C, D, E, and F, running longitudinally through the fence, and the double 15 pickets G, having curved tops, which overlap or cross each other above the top of the horizontal strand or wire A and which have parallel portions g, extending the distance between the strands or wires A and B, and the 20 inclined portions g', converging toward each other through the space between the strands or wires B and C, and the parallel portions

G², extending through the space between the strands or wires C and D, and the inclined portions g³, diverging from each other through the space between the strands or wires D and E, and the inclined portions G⁴, converging toward each other through the space between the strands or wires E and F, and the single pickets H, inserted between the double pickets G, so as to vertically bisect the diamond spaces formed by the converging and diverging portions g', g³, and g⁴ of the double pickets, the whole presenting an attractive and ornate appearance, as shown in the drawing. 30 35

What I regard as new, and desire to secure by Letters Patent, is—

The design for a wire fence herein shown and described.

JESSE H. SROFE.
